UNITED STATES PATENT OFFICE.

FRED R. BARTHOLOMEW, FRANK J. VIERLING, AND ORLO A. BARTHOLOMEW, OF MINNEAPOLIS, MINNESOTA, ASSIGNORS TO STERLING SPECIALTIES MANUFACTURING COMPANY.

PENCIL.

Application filed May 9, 1921. Serial No. 468,082.

To all whom it may concern:

Be it known that we, FRED R. BARTHOLOMEW, FRANK J. VIERLING, and ORLO A. BARTHOLOMEW, are citizens of the United States, residing at Minneapolis, in the county of Hennepin and State of Minnesota, have invented certain new and useful Improvements in Pencils; and we do hereby declare the following to be a full, clear, and exact description of the invention, such as will enable others skilled in the art to which it appertains to make and use the same.

Our invention relates to improvements in pencils of the type disclosed and claimed in the pending application of Fred R. Bartholomew and Frank J. Vierling, filed September 30, 1920, under Serial Number 413,708, and has for its object to improve the same in the several particulars herein- after noted.

To the above end, generally stated, the invention consists of the novel devices and combination of devices hereinafter described and defined in the claims.

In the accompanying drawings which illustrate the invention, like characters indicate like parts throughout the several views.

Referring to the drawings:—

Fig. 1 is a side elevation of the pencil having the invention embodied therein;

Fig. 2 is a view partly in side elevation and partly in longitudinal central section;

Fig. 3 is a view in longitudinal central section taken on the line 3—3' of Fig. 2, with the casing removed;

Figs. 4, 5 and 6 are views in transverse sections taken on the lines 4—4, 5—5 and 6—6 of Fig. 2, on an enlarged scale;

Fig. 7 is a detail view of the lead-holding stem; and

Fig. 8 is a fragmentary detail view in section taken on the line 8—8 of Fig. 2 and illustrating how a piece of lead may be removed from the lead chamber.

The numeral 9 indicates a casing that is hexagonal in cross section, both inside and outside, throughout its entire length, except at one end, which is tapered to afford a point 10. A cylindrical cap tube 11 is loosely telescoped part way into the casing 9, and pressed onto the outer end thereof is a cap tube extension 12, the lower end of which, as shown, loosely extends into the upper end of the casing 9. An external

annular bead 13, on the cap tube extension 12, engages the upper end of the casing 9 as a stop. The upper end of the cap tube extension 12 is tapered above the bead 13 to receive and frictionally hold a removable cap 14. A tubular feed screw 15 is carried by the cap tube 11 and is rigidly secured thereto by contracting the lower end of said cap tube onto the screw-threaded upper end of said feed screw. The lower end of the feed screw 15 is tapered at 16 to afford a bearing seated against the internal wall of the point 10, and which bearing holds said feed screw and the cap tube 11 against lateral movement and in axial alignment with the nose or lower end of the point 10, through which a piece of lead may be fed, as will presently appear.

The upper end of the cap tube 11 is rotatively mounted in a longitudinally split bearing sleeve 17 held against axial movement between the cap tube extension 12 and an external annular bead 18 on said tube 11. Primarily, the bearing sleeve 17 loosely fits around the cap tube 11 and when inserted into the casing 9, together with the cap tube 11 and feed screw 15, is contracted by said casing onto the cap tube 11 and held against rotation by its frictional engagement with said casing. To assist in causing the bearing sleeve 17 to enter the casing 9, the lower end thereof, is beveled at 19, and to still further assist in causing the said sleeve bearing to enter the casing, the same is primarily tapered by contracting the lower end thereof, as shown in Fig. 3. Obviously, the bearing 16 and bearing sleeve 17 hold the cap tube 11 and feed screw 15 with freedom for rotation in the casing 9. To yieldingly and releasably hold the cap tube 11 and feed screw 15 against removal from the casing 9, there is pressed inward from said casing, a pair of diametrically opposite points or lugs 20, which extend into an annular groove 21 formed in the bearing sleeve 17.

Axially movable in the tubular feed screw 15, which forms a portion of the lead feeding mechanism, is a tubular lead feeding stem 22, formed, as shown, by folding a single sheet around a pin 23 having a radially extended blade 24 at its upper end which works in a longitudinally extended guide slot 25 in the feed screw 15. Endwise movement is imparted to the feed stem 22 by

notching its blade 24 to receive a hexagon nut 26 on the feed screw 15. This hexagon nut 26 is held against rotation by the hexagon casing 9, but with freedom for axial 5 traveling movement therein. The blade 24 is held in the slot 25 against turning movement, but is free to move endwise with the nut 26. On the lower end of the lead feeding stem 22, below the pin 23, is a pair of 10 yielding jaws 27 adapted to receive and hold one end of a piece of lead Z, said lead being in position to move in the feed screw 15 and through the nose of the point 10, under the traveling action of the nut 26, imparted 15 thereto by turning the cap tube extension 12 in respect to the casing 9.

The cap tube 11 affords a lead chamber 28 having a longitudinally extended entrance passageway 29, through which said 20 chamber may be filled with extra leads Z¹, or said leads removed therefrom. The ends of the lead chamber 28 are closed by flanged disks 30 pressed into the cap tube 11 and it is important to note that the uppermost 25 of said disks is located considerably above the entrance passageway 29. An eraser 31 is secured in the upper end of the cap tube extension 12. The entrance passageway 29 in the lead chamber 28 is normally closed 30 by a longitudinally divided sleeve 32 rotatively mounted on the cap tube 11 and held against axial movement by the bead 18 and an annular bead 33 pressed from said cap tube. The longitudinal edges of the sleeve 35 32 are spaced to afford, therebetween, an entrance passageway 34 adapted to be brought into alignment with the passageway 29 to open the lead chamber 28, as best shown in Fig. 5. To remove one of the leads Z¹ 40 from the lead chamber 28, an endwise pull on the cap tube extension 12 will spring the points 20 out of the groove 21 and permit the pencil to be removed from its casing 9 after which the sleeve 32 may be rotated to 45 open the passageway 29 to the lead chamber 28. While the pencil is still held by the cap tube extension 12, the same may be inverted and given a slight lateral shake to cause one of said leads to project through 50 the passageway 29, as best shown in Fig. 8. It will be noted that the lead Z¹, which extends through the passageway 29, is held in its inclined position by engagement with one end of said passageway, which, as previously stated, is spaced inward of the upper 55 disk 30. Preferably, as shown, the passageway 29 is of less length than the normal length of the lead Z¹ so that said leads are not so liable to drop out of the passageway 60 29 when the pencil is turned on its side. When the lead feeding mechanism is used in connection with a pencil having a round casing, the sleeve 32 may be dispensed with for the reason that such casing would close 65 the entrance passageway 29, but in a pencil

having a hexagon casing, the sleeve 32 is highly important for the reason that the cap tube does not closely engage the walls of such casing. However, the sleeve 32 is important, irrespective of the form of the 70 pencil casing for the reason that it closes the lead chamber 28 when the lead feeding mechanism is removed from the casing.

The above invention has, in actual usage, proven highly efficient for the purpose had 75 in view.

What we claim is:

1. A pencil comprising a casing, a cap tube, a contractible and expansible bearing sleeve on the cap tube and insertible therewith into the casing, said bearing sleeve being arranged to be contracted onto the cap tube by its insertion into the casing, and lead-feeding mechanism carried by the tube. 80

2. A pencil comprising a casing, a cap tube, a longitudinally divided contractible and expansible bearing sleeve on the cap tube and insertible therewith into the casing, said bearing sleeve being arranged to be contracted onto the cap tube by its insertion into the casing, and lead-feeding mechanism carried by the tube. 85

3. A pencil comprising a casing, a cap tube, a longitudinally divided contractible and expansible bearing sleeve on the cap 90 tube and insertible therewith into the casing, said bearing sleeve being arranged to be contracted onto the cap tube by its insertion into the casing, means on the cap tube for holding the bearing sleeve against axial movement thereon, and lead-feeding mechanism carried by the tube.

4. A pencil comprising a casing, a cap tube, a longitudinally divided contractible and expansible bearing sleeve on the cap 10 tube and insertible therewith into the casing, said bearing sleeve being arranged to be contracted onto the cap tube by its insertion into the casing, means on the cap tube for holding the bearing sleeve against axial movement thereon, said bearing sleeve and casing having yielding interlocking engagement to hold the bearing sleeve and cap tube against axial movement in the casing, and lead-feeding mechanism carried by the 11 tube. 11

5. A pencil comprising a casing, a cap tube, a longitudinally divided contractible and expansible bearing sleeve on the cap tube and insertible therewith into the casing, said bearing sleeve being arranged to be contracted onto the cap tube by its insertion into the casing, means on the cap tube for holding the bearing sleeve against axial movement thereon, said bearing sleeve and casing having yielding interlocking engagement to hold the bearing sleeve and cap tube against axial movement in the casing, the lower end of the bearing sleeve being 12 beveled for engagement with the casing to 13

- cause the same to be contracted thereby during its insertion into the casing, and lead-feeding mechanism carried by the tube.
6. A pencil comprising a casing, a cap tube, a loose longitudinally divided contractible and expansible bearing sleeve on the cap tube and insertible therewith into the casing, said bearing sleeve being arranged to be contracted onto the cap tube by its insertion into the casing, means on the cap tube for holding the bearing sleeve against axial movement thereon, said bearing sleeve and casing having yielding interlocking engagement to hold the bearing sleeve and cap tube against axial movement in the casing but free to rotate in respect thereto, and lead-feeding mechanism carried by the tube.
7. A pencil comprising a casing, a cap tube in the casing, a cap tube extension telescoped onto the cap tube, a bearing sleeve in which the cap tube is rotatively mounted, said bearing sleeve being held by the casing against rotation and held against axial movement on the cap tube by the cap tube extension and a bead on the cap tube, and lead-feeding mechanism carried by the cap tube.
8. A pencil comprising a casing, a cap tube telescopically mounted in the casing affording a lead chamber having a longitudinal entrance passageway so arranged that a lead in the lead chamber may be tipped into a position in which it projects obliquely out of said passageway, and lead-feeding mechanism carried by the tube.
9. A pencil comprising a casing, a cap tube, telescopically mounted in the casing, affording a lead chamber having a longitudinal entrance passageway normally within the casing, the bottom of the lead chamber being below the entrance passageway whereby, when the cap tube is withdrawn from the casing sufficiently to expose the entrance passageway, a lead in the lead chamber may be tipped, while resting on said bottom, so that one end thereof projects through the entrance passageway and is supported in an oblique position, and lead feeding mechanism carried by the cap tube.
10. A pencil comprising a casing, a cap tube, telescopically mounted in the casing, affording a lead chamber having a longitudinal entrance passageway normally within the casing, a sleeve mounted on the cap tube, normally closing the entrance passageway and movable into a position to open said passageway, and lead operating mechanism carried by the cap tube.
11. A pencil comprising a casing, a cap tube, telescopically mounted in the casing, affording a lead chamber and having a longitudinal entrance passageway normally within the casing, a sleeve rotatively mounted in the casing, normally closing the passageway and having a passageway arranged to be brought into registration with the passageway in the cap tube, and lead-operating mechanism carried by the cap tube.
12. A pencil comprising a casing, a cap tube, telescopically mounted in the casing, affording a lead chamber and having a longitudinal entrance passageway normally within the casing, and a longitudinally divided sleeve, the longitudinal edges of which are spread to afford a passageway therebetween, said sleeve being rotatively mounted on the cap tube, normally closing the passageway in said cap tube and adapted to be rotated into a position to bring its passageway into registration with the passageway in the cap tube, and lead-operating mechanism carried by the cap tube.
13. A pencil comprising a casing, a cap tube in the casing affording a lead chamber and having a longitudinal entrance passageway, and a longitudinally divided sleeve, the longitudinal edges of which are spaced to afford a passageway therebetween, said sleeve being rotatively mounted on the cap tube, normally closing the passageway in said cap tube and adapted to be rotated into a position to bring its passageway into registration with the passageway in the cap tube, beads on the cap tube holding the sleeve against axial movement, and lead-operating mechanism carried by the cap tube.
14. A pencil comprising a casing, a cap tube in the casing, a longitudinally divided bearing sleeve in which the cap tube is rotatively mounted and which bearing sleeve is held against axial movement on the cap tube, said bearing sleeve being adapted to be contracted by the casing when the cap tube is inserted therein and held by said casing against rotation, an annular groove and a projection extending therein, said groove and projection being formed, the one in the casing and the other in the bearing sleeve for releasably holding said cap tube against axial movement in the casing but with freedom for rotary movement in the bearing sleeve, and lead-feeding-mechanism carried by the cap tube.

In testimony whereof they affix their signatures.
